UNITED STATES PATENT OFFICE.

EBERHARD FABER, OF NEW YORK, N. Y.

DESIGN FOR A DISPLAY-CASE.

No. 37,877.

Specification for Design.

Patented March 6, 1906.

Application filed July 31, 1905. Serial No. 272,137. Term of patent 7 years.

To all whom it may concern:

Be it known that I, EBERHARD FABER, a citizen of the United States, residing at New York, in the county and State of New York, have invented a new, original, and ornamental Design for Display-Cases, of which the following is a specification, reference being had to the accompanying drawing, forming part hereof.

The figure is a front elevation of a display-case, showing the design applied thereto.

I claim—

The ornamental design for a display-case as shown.

EBERHARD FABER.
